UNITED STATES PATENT OFFICE.

HENRY VAN HOEVENBERGH, OF ELIZABETH, NEW JERSEY, ASSIGNOR TO
THE BALTIMORE & OHIO TELEGRAPH COMPANY, OF BALTIMORE, MD.

TYPE-WHEEL FOR PRINTING-TELEGRAPHS.

SPECIFICATION forming part of Letters Patent No. 316,684, dated April 28, 1885.

Application filed August 7, 1884. (No model.)

To all whom it may concern:

Be it known that I, HENRY VAN HOEVENBERGH, a citizen of the United States, residing in Elizabeth, in the county of Union and State 5 of New Jersey, have invented certain new and useful Improvements in Type-Wheels for Printing-Telegraphs, of which the following is a specification.

My invention relates to the construction of 10 type-wheels for printing-telegraph instruments.

The object of the invention is to provide means for effecting impressions from either of 15 two type-wheels at will without the aid of complicated mechanism.

The invention consists in mounting two type-wheels of different diameters on the same shaft, the one type-wheel being rigidly secured to the shaft, while the remaining type-wheel is 20 loosely mounted upon the same. Means are provided for locking the second type-wheel to the first-named type-wheel or to its shaft and for unlocking it therefrom at the will of the transmitting-operator.

25 In carrying out my invention I secure the smaller type-wheel rigidly to a type-wheel shaft which is provided with any suitable means for producing a step-by-step motion. The larger type-wheel is carried upon a sleeve 30 loosely surrounding the shaft, and is capable of being locked thereto by means of a coupling-pin which extends toward the lateral surface of the smaller type-wheel. The smaller type-wheel is designed to carry those characters 35 which are more frequently employed in printing—such, for instance, as the more important letters of the alphabet—while the larger type-wheel is designed to carry the less important letters, the numerals, and such other characters as are desired less frequently. The periphery of the larger type-wheel is cut away 40 at one point a sufficient distance to expose a section of the smaller wheel. A single printing-platen is employed for effecting impressions from both type-wheels. This platen will cause impressions to be taken from the larger type-wheel except when that type-wheel is arrested in such a position that the point

where its periphery is cut away is presented to the printing-platen. When, therefore, it is 50 desired to effect impressions from the smaller type-wheel, the larger type-wheel is arrested in such a position that this point will be above the platen, and it is at the same time unlocked from the smaller type-wheel and held in that 55 position. By then revolving the smaller type-wheel any desired character upon its periphery may be presented to the platen, and impressions will be taken therefrom in the usual manner. When it is desired to effect an impression from the larger type-wheel, the latter is locked to the smaller type-wheel and permitted to revolve therewith. Any desired character upon its periphery may then be brought 60 above the platen, which, upon being actuated, 65 will effect impressions therefrom to the exclusion of the characters upon the smaller type-wheel, for the reason that the platen will be prevented from making contact with the smaller by striking against the periphery of 70 the larger type-wheel.

The means which I prefer to employ for locking and unlocking the two type-wheels consist of a pin extending through the larger type-wheel toward the smaller type-wheel, in 75 the direction of which it is normally forced by means of a suitable spring. This pin is designed to enter an aperture formed in the smaller type-wheel, and when it is released from a lever controlled by an electro-magnet 80 it serves to lock the two wheels together. The electro-magnet may be either a polarized electro-magnet designed to respond to currents of different polarities or it may be a neutral electro-magnet, the armature-lever being actuated 85 in one direction by a spring and in the opposite direction through the action of electric currents. The electro-magnet may be included in the circuit of the main line through which are transmitted the currents employed for actuating the escapement and the printing-lever, or an independent conductor may be employed.

In another application of even date here-with, Serial No. 139,880, certain devices are shown which in some respects resemble those 95 shown herein, and I do not herein claim any

of the devices shown, described, and claimed in such other application and not specifically claimed herein.

In the accompanying drawings, Figure 1 shows in elevation such parts of a printing-telegraph instrument as are necessary to illustrate my invention; and Fig. 2 is a plan of the same, partly in section, showing certain details in the organization of the locking and unlocking device of the type-wheel.

Referring to the drawings, A represents the type-wheel shaft, upon which is rigidly mounted a type-wheel, B, of usual construction. Upon a sleeve, c' , is carried a second type-wheel, the diameter of which is slightly greater than that of the type-wheel B. The type-wheel C is constructed in the same manner as the type-wheel B, with the exception that at one point in its periphery the wheel is cut away, as shown at c^2 , to a depth somewhat beyond the periphery of the wheel B. It is designed that when the type-wheel C is not in operation it shall be arrested with the point c^2 above the printing-platen D of the instrument. Impressions will then be taken from the type-wheel B by means of the printing-platen in the usual manner. If, however, the type-wheel C be locked to the type-wheel B, and revolved so that its characters are brought in succession above the platen, impressions will be taken from the larger type-wheel, but no impression will be taken from the type-wheel B for the reason that the platen is prevented from carrying the paper into contact therewith.

For the purpose of locking and unlocking the type-wheels, a pin, e, is employed, which passes through a sleeve carried upon the type-wheel C, and is pressed toward the type-wheel B by means of a spring, f. The pin e is intended to enter a hole, g, formed in the side of the type-wheel B, and to thereby lock the type-wheels together. The hole and the pin are preferably so arranged with reference to each other that when the two wheels are locked together the opening c^2 shall be parallel with the blank or unison-point in the type-wheel B. This construction, however, is not essential, as any desired character may be substituted for the blank or space point.

The means which I prefer to employ for controlling the locking and unlocking device consist of an electro-magnet, M, which may be included in the main-line circuit or in the circuit of an independent conductor, as desired. This electro-magnet is provided with an armature, m, carried upon an armature-lever m' . At the end of the armature-lever m' is carried a hook or forked catch, m^2 , which is designed to engage a projection, f' , carried upon the pin e. When the type-wheels have been arrested in a given position—that is to say, with the open space c^2 of the type-wheel C above the printing-platen—if, then, the electro-magnet M be vitalized and the armature m impelled away from the type-wheel, the catch m^2 will engage the extension f' of the pin e and with-

draw it from engagement with the type-wheel B. The latter may then be actuated independently of the type-wheel C, which is held in the position which it last assumed by reason of the forked catch m^2 engaging the extension f' upon both sides. The armature m will remain in the position away from the type-wheel until the electro-magnet is again demagnetized and it is drawn back by the retractile spring s.

It is designed that the electro-magnet M, when it is included in the main-line circuit, shall respond only to currents of a different polarity or of greater strength than are employed for actuating the escapement device and the printing-magnet. When, however, the electro-magnet is included in a special wire, currents of any desired strength may be employed.

Any suitable form of unison device may be adapted to the instrument as found convenient.

It is essential that the type-wheel B should be in unison with the transmitting device when it is desired to lock the type-wheel C thereto. Otherwise the pin e, upon being released, would strike against the surface of the type-wheel B without entering the aperture g. If, however, the pin should be released when the type-wheel B is not in unison, a shoulder, m^3 , carried upon the lever m' , will engage with the pin e after it has been released from the fork m^2 and hold it until it shall have entered the aperture g, formed in the type-wheel B. The type-wheel C will therefore remain at its unison-point, although released from the fork, until the pin e has engaged the type-wheel B.

I claim as my invention—

1. The combination, substantially as hereinbefore set forth, of a type-wheel shaft and two type-wheels carried thereon, one of which is of greater diameter than the other and has a portion of its periphery cut away.

2. The combination, substantially as hereinbefore set forth, with a type-wheel shaft of a printing-telegraph instrument, of a type-wheel rigidly secured thereto, and a second type-wheel having a greater diameter than the first-named type-wheel loosely mounted upon said type-wheel shaft and having a portion of its periphery cut away.

3. The combination, substantially as hereinbefore set forth, of a type-wheel shaft, a type-wheel rigidly carried thereon, a second type-wheel having a greater diameter than the first-named type-wheel, and having a cut-away portion, and means, substantially such as described, for locking the second type-wheel to said shaft.

4. The combination, substantially as hereinbefore set forth, of a type-wheel shaft, a type-wheel rigidly secured thereto, a second type-wheel loosely mounted thereon, a device for coupling said type-wheels together, and an electro-magnet for controlling said device, and means for printing from either of the type-wheels.

5. The combination, substantially as herein-before set forth, in a printing-telegraph instrument, with the type-wheel shaft and a type-wheel rigidly secured thereto, of a second 5 type-wheel having a portion of its periphery cut away, a device for locking said second type-wheel to the first-named type-wheel at the will of the transmitting-operator, and means, substantially such as described, for unlocking said second type-wheel from the first-named type-wheel and holding it in such position that the portion of its periphery which is cut away is presented to the printing-platen of the instrument.
- 10 6. The combination, substantially as herein-before set forth, of a type-wheel shaft, two independently movable type-wheels, a pin for locking said type-wheels together, and an electro-magnet, its armature and armature-lever 20 serving to engage said pin and remove it from engagement with one of said type-wheels and to retain the other type-wheel in a given position at the will of the transmitting-operator.
- 15 7. The combination, substantially as herein-before set forth, with a type-wheel shaft and two type-wheels of different sizes carried thereon, the larger of which is cut away through a portion of its periphery, of a printing-platen for effecting impressions from the one type-wheel or the other accordingly as the portion 30 of the latter type-wheel which is cut away is or is not presented to the printing-platen.
8. The combination, substantially as herein-before set forth, with a type-wheel shaft and two type-wheels, one of which is attached to said shaft while the other is movable upon the same, of means, substantially such as described, for coupling said type-wheels together, an electro-magnet, its armature and armature-lever, and a detent carried upon said movable 40 type-wheel, which detent by contact with said lever arrests said type-wheel in a predetermined position.
9. The combination, substantially as herein-before set forth, with a type-wheel shaft and two type-wheels, one of which is rigidly supported upon said shaft while the other is movable thereupon, of a pin for locking said type-wheels together, an electro-magnet, its armature and armature-lever for controlling said pin, which pin serves as a detent for arresting 45
- 50 said type-wheels in a given position, substantially as described.
10. The combination, substantially as herein-before set forth, with a type-wheel shaft and two type-wheels carried thereon, of a pin for locking said type-wheels together, and an electro-magnet for withdrawing said pin from one of said type-wheels and for arresting the other of said type-wheels in a given position, which pin by making contact with said armature-lever serves to arrest said type-wheel in a predetermined position.
11. The combination, substantially as herein-before set forth, with two type-wheels one 65 of which is movable independently of the other, and means, substantially such as described, for coupling the same together, of a unison-stop carried upon one of said type-wheels, and an electro-magnet, its armature and armature-lever for engaging said unison-stop and for controlling said coupling device, substantially as described.
12. The combination, substantially as herein-before set forth, with two type-wheels one 75 of which is movable independently of the other, and a unison-stop carried upon one of said type-wheels, of a device for coupling said type-wheels together, and an electro-magnet, its armature and armature-lever for controlling said coupling device, which lever when in position to permit said type-wheels to be locked together is out of the path of said unison-stop.
13. The combination, substantially as herein-before set forth, with a type-wheel shaft and two type-wheels carried thereon one of which is movable independently of the other, of a pin for locking said type-wheels together, and an electro-magnet, its armature and armature-lever for controlling said locking-pin, which pin serves as a unison-stop, and is engaged by said armature-lever before said locking device is in position to be actuated by said armature-lever, substantially as described.
- 85 90 95 In testimony whereof I have hereunto subscribed my name this 14th day of April, A. D. 1884.
